GUY WIRE FASTENER

Robert Schaedler, Hatfield, Pa.

Application May 15, 1936, Serial No. 80,011

1 Claim. (Cl. 24—136)

The present invention relates to new and useful improvements in guy wire fasteners particularly for telephone, telegraph or electric light poles, etc., although it will be understood, of course, that the device may be used for any purpose for which it may be found adapted and desirable.

The primary object of the invention is to provide, in a manner as hereinafter set forth, a fastener of the aforementioned character embodying novel means through the medium of which a guy wire or the like may be securely fastened without the usual clamps, bolts, etc., the construction and arrangement being such that the grip on the guy wire or the like will be increased as the pull is increased.

Another very important object of the invention is to provide a fastener of the character described in which the guy wire or the like may be expeditiously engaged with a minimum of labor.

Other objects of the invention are to provide a guy wire fastener which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views and wherein:—

Figure 1 is a view in front elevation of the invention, showing a guy wire clamped therein.

Figure 2 is a view in side elevation of the device.

Figure 3 is a cross sectional view, taken substantially on the line 3—3 of Figure 1.

Figure 4 is a vertical sectional view through the invention, taken substantially on the line 4—4 of Figure 2.

Figure 5 is a view in front elevation, showing the device before the guy wire has been clamped therein, the pull bars being broken away.

Referring now to the drawings in detail, it will be seen that the embodiment of the invention which has been illustrated comprises a substantially ovate plate 1 of suitable metal having formed therein a longitudinal slot 2. Formed in the periphery of the plate 1 is a groove 3 for the reception of a guy wire or the like 4. As best seen in Figure 2 of the drawings, the groove 3 is spirally ribbed for a better grip on the guy wire 4. Also formed in the periphery

of the plate 1, at intermediate points, are arcuate recesses 5.

The reference numeral 6 designates a pin which is adapted to travel in the slot 2. Journalled on the pin 6 are what may be referred to as pull bars 7 having openings 8 in their free end portions. Also pivotally mounted on the pin 6 are diverging pairs of links 9 between the free end portions of which grooved rollers 10 are journalled. The rollers 10 are adapted to press 10 the guy wire 4 into the recesses 5.

The reference numeral 11 designates a pair of elongated plates which extend transversely across the small end portion of the plate 1 and between the end portions of which grooved rollers 15 12 are journalled. Pairs of links 13 have one end pivotally connected to the plates 11 and their other ends pivotally connected to the outer end portions of the links 9.

It is thought that the operation of the device 20 will be readily apparent from a consideration of the foregoing. To engage the guy wire 4 in the fastener, the pin 6 is pushed upwardly or forwardly in the slot 2 in a manner to expand the rollers 10, as clearly shown in Figure 5 of the 25 drawings, and move the rollers 12 away from the small end of the plate 1. The guy wire 4 may then be conveniently inserted between the rollers 12 and 10 on one side of the plate 1, brought around the large end of said plate and 30 then inserted between the rollers 10 and 12 and the plate on the other side of said plate. The bars 7 are then pulled in a manner to move the pin 6 downwardly or rearwardly in the slot 2, thereby swinging the rollers 10 inwardly for 35 clamping the guy wire 4 tightly in the recesses 5 while at the same time shifting the rollers 12 toward the plate 1 for gripping the guy wire therebetween. This is shown to advantage in Figure 4 of the drawings. It will thus be seen 40 that the guy wire will be securely fastened and it will further be noted that the greater the pull that is exerted the tighter the guy wire will be gripped. The reference numeral 14 designates pins which connect the links 9 and 13 and on 45 which the rollers 10 are journalled and the reference numeral 15 designates pins which connect said links 13 and the plates 11 and on which the rollers 12 are journalled.

It is believed that the many advantages of a 50 fastening device constructed in accordance with the present invention will be readily understood and although a preferred embodiment of said device is as illustrated and described, it is to be understood that changes in the details of con- 55

struction and in the combination and arrangement of parts may be resorted to which will fall within the scope of the invention as claimed.

What is claimed is:

- 5 A fastener of the class described comprising a substantially ovate plate having a peripheral groove therein for the reception of a guy wire, said plate further having substantially arcuate recesses therein at an intermediate point, said 10 plates still further having a longitudinal slot therein, a pin operable in the slot, pull bars pivotally connected to said pin, pairs of diverging links pivotally connected to the pin, grooved gripping rollers journaled between the outer

end portions of said links, a pair of elongated plates extending transversely across the small end of the first named plate, rollers journaled between the end portions of the second named plates, the first and second named rollers and the first named plates being adapted to grip the guy wire therebetween, the first named rollers being engageable in the recesses, and pairs of links pivotally connected, at one end, to the end portions of the second named plates and at 10 their other ends to the outer end portions of the first named links.

ROBERT SCHAEDELER.
